ATTORNEY

tures 24 is less than the diameter of the sleeve bore 22 to provide a shoulder 25 between the upper jaw aperture 24 and the sleeve bore 22, for the purpose to be described.

A cylindrical latching member 26 is mounted and longitudinally slidable in the sleeve bore 22, and normally extends in the latching position through the apertures 24 in the jaws 19 and 20. The upper end of the latching member 26 is provided with an outwardly disposed annular flange 27, which is adapted for engaging the shoulder 25 for preventing the latching member 26 from passing entirely through the jaw apertures 24.

The latching member 26 is provided with a deep pocket 26' for seating the lower end of a spiral actuating spring 28. The upper end of the latter is seated in a pocket 28, formed in the adjusting plug 30. The latter is threadedly engaged in the threaded bore portion 23 and adjustable therein to establish the desired tension to the spring 28. The action of the spring 28 normally forces the latching member 26 downwardly to the latching position through the jaw apertures 24, as shown in Figure 3.

When the arm 11 is in the holding position, the head 17 thereof is disposed between the jaws 19 and 20, and the aperture 18 of said head 17, is in exact registration with the jaw apertures 24, allowing the latching member 26 to extend through both jaw apertures 24 and through the head aperture 18, and thereby securing the arm 11 in the holding position, as clearly illustrated in Figure 3.

To release the arm head 17 from the jaws 19 and 20, the latching member 26 is forced upwardly into the sleeve bore 22, by means of any suitable implement, until the lower rounded end 31 of said latching member 26 clears the arm head 17.

A spring controlled locking rod 32 is shiftably mounted in the joined side of the upper jaw 19, and has its inner end projecting into the upper aperture 24 of the jaw 19. The locking rod 32 extends horizontally and is provided for locking the latching member 26 in the latched and released positions.

The latching member 26 is provided with a pair of circumferentially extending grooves, indicated at 33 and 34, which are adapted for engagement by the projecting inner end of the locking rod 32. When the upper groove 33 is engaged by the locking rod 32, as shown in Figure 3, the latching member 26 is locked in the latched position. When the latching member 26 is forced to the released position, the locking rod 32 will engage in the lower groove 34 and lock said latching member 26 in the released position. The latching member 26 is released from either of the locked positions by pulling the locking rod 32 outwardly until the inner end thereof clears respective grooves 33 and 34.

The present invention provides a most efficient device of its kind, which is conveniently operable for holding or releasing the tool from the hammer, whereby tool changing and manipulations are greatly facilitated and expedited.

What I claim is:

In combination, a tool retainer for a power operated hammer comprising a holding arm having one end thereof pivotally attached to the hammer, a connecting sleeve secure to the hammer, a pair of spaced jaws carried by said connecting sleeve for receiving the free end of said holding arm, a spring actuated latching member connecting with said sleeve and shiftable in the latter for securing and releasing said free end of said holding arm, said latching member being provided with a pair of circumferentially extending grooves disposed adjacent to respective ends thereof, a spring controlled locking rod mounted in one of said pair of jaws and normally operable for engaging in one of said pair of grooves for holding said latching member in the secured position and in the other of said grooves for holding the latching member in the released position, and means mounted in said sleeve for adjusting the spring actuating said latching member.
